GRAPPLER FOR SUNKEN SHIPS

Filed April 9, 1928

UNITED STATES PATENT OFFICE.

ELMER C. JACOBSON, OF ROY, WASHINGTON, ASSIGNOR OF ONE-FOURTH TO ALFRED A. HENN AND ONE-FOURTH TO LILY REICHMAN, BOTH OF TACOMA, WASHINGTON.

GRAPPLE FOR SUNKEN SHIPS.

Application filed April 9, 1928. Serial No. 268,517.

This invention relates to devices for raising sunken ships and especially to devices for locating the position of the wreck and for attaching thereto a grapple whereby it may be raised. The objects of my invention are, first, to provide a suitable means, permanently attached to the ship hull, whereby the hull may be raised when sunk; second, to provide a light extension to said means, with 5 floating buoy or raft mounted thereon, whereby the wreck may be located; and third, to provide a grapple means adapted to be guided to said raising means on the ship by said light extension thereof, and to grip said raising 10 means, and including suitable apparatus whereby the ship may be raised. Other objects are to provide an improved form of 15 grapple, which may be quickly opened up to connect it to the guiding means, and which 20 will slide freely down said guiding means, and down said raising means, and which will firmly grip said raising means when it, the grapple, is raised thereon, but will not grip 25 said guiding means if raised before it reaches the raising means; a further object is to improve the gripping means on said grapple, whereby the strain of the gripping action is transferred through the gripping dogs direct 30 to the grapple body, without passing through the pivots of said dogs. A further object is to provide a device which is simple in its construction, cheap to make, and effective in use.

I attain these and other objects by the devices, mechanisms, and arrangements illustrated in the accompanying drawings, in which:—

Figs. 1, 2, 3 and 4 are diagrammatic views showing the several stages in raising a sunken ship, Fig. 1 showing the ship as sunk with the floating buoy indicating its position; Fig. 2 shows the grapple being attached to the guide line; Fig. 3 shows the grapple being lowered down the guide line to the ship; and Fig. 4 shows the ship being raised by the grapple engaging the attachment on the hull; Fig. 5 is a perspective view of the grapple; Fig. 6 is an elevation of the inner surface of a part thereof with the grapple dogs removed therefrom; Fig. 7 is a similar view showing the

parts in the position when sliding down the attachment on the hull; Fig. 8 is a similar view showing the dogs in gripping engagement with the said attachment; Fig. 9 is an elevation of the upper end of the said hull 55 attachment, showing its connection to the light guiding line, and showing the grapple being lowered down the guiding line; and Fig. 10 is a section of the grapple, with the gripping dogs removed therefrom. Similar 60 numerals of reference refer to similar parts throughout the several views.

The main problems in salvaging sunken ships are, first, the location of the wreck, and, second, the attachment thereto of suitable 65 raising tackle.

Referring to the drawings, it will be seen that I have solved both of these problems with the apparatus illustrated therein. It is to be understood that, though the illustration shows 70 only one such apparatus applied to the ship, it is not intended to limit it to any particular number but that as many similar appliances as are needed for the purpose will be provided, in such places thereon as is desired, and that 75 they will be used in cooperation to effect the complete salvaging of the wreck.

The ship hull 1 is, therefore, provided with a short heavy cable 2, suitably and permanently attached to the hull framing in such manner as to reduce the strain thereon as much as possible. This short cable 2 may usually be laid on the deck, out of the way, and has a very long light line 3 permanently attached to its end. This light line 3 may be coiled on 85 a drum, or otherwise stowed, and has a loop 4 at its end. A buoy or raft 5 is stored on the deck of the ship 1, adjacent the apparatus, and the light line 3 is attached thereto adjacent the said looped end 4. Thus it will be 90 seen that, when the ship 1 sinks, the buoy or raft 5 will rise from the deck and carry the end of the line 3 up to the surface of the sea (Fig. 1), it being understood that a sufficient length of such line 3 is provided to reach the 95 surface of the sea from any depth on the usual course of the ship. Thus the buoys or rafts 5 will make an effective marker from which salvaging operations may be conducted.

As soon, therefore, as the ship owner is 100

advised as to which of his vessels has been sunk he knows the number and size of grapping apparatus to send to the site marked by such buoys, one grapping apparatus being provided for each such raft 5. On the arrival of this salvaging fleet, the first step taken is to pull upward on the light line 3 until it is evident that the slack has been substantially taken therefrom (Fig. 2). Then the wrecker 10 6, which may be any form of floating vessel, and which carries the grapple apparatus, raising cable, and operating machinery thereon, is brought to the raft 5 and the grapple 7, hereinafter described, is lowered therefrom 15 to the raft 5. The grapple 7 is then opened to admit the line 3 therein, and then is bolted closed thereon. After it has thus been mounted on the line 3, the grapple 7 is lowered by its own heavy cable 8 (Fig. 3) from the vessel 20 6, and by the suitable machinery thereon, while the light line 3 is kept taut, in order to guide the grapple 7 to the cable 2, until the said grapple 7 passes over the joint between the main fixed short cable 2 and the guide line 25 3. This point may be readily ascertained by periodically reversing the movement of the grapple 7 on the line 3 since the gripping apparatus therein will not clamp on the light line 3 (Fig. 9) and therefore the strain on the 30 cable 8 will not be increased until the grapple 7 has reached the cable 2. When this point has thus been reached by the grapple 7, it is then lowered a sufficient additional distance to be sure that the cable 2 has passed entirely 35 through it, and then the cable 8 may be raised by the machinery on the vessel 6 and, in so doing, the grapple 7 grips the cable 2 and raises the ship 1 thereby.

Referring to Fig. 9 it will be seen that the 40 joint between the heavy cable 2 and the light cable 3 is formed by a long gradual cone 9, which insures that the cable 2 will properly thread itself through the grapple 7, as it is passed thereover.

Referring to Fig. 5, it will be seen that the 45 grapple 7 comprises two heavy plates 10 and 11, hinged together at 12, on one edge, and secured together by a bolt 13 near the other edge. A complementary pair of vertical 50 grooves 14 run upward on the two contiguous faces of the said plates 10 and 11, thus forming a single passage, extending from end to end, adapted to pass freely over the large heavy cable 2 mounted on the ship hull 1. 55 The two parts 10 and 11 are each provided with a heavy trunnion or pin 15, extending from their outer faces, on which a pair of supporting links 16 are mounted, said links 16 being looped around the loop 17 formed in 60 the end of the heavy hoisting cable 8.

The contiguous faces of the two parts 10 and 11 of the grapple are also provided with complementary recesses 18, extending across the said parts 10 and 11 and together forming 65 chambers or slots (Fig. 10) on each side of the

central vertical cable groove 14. The lower sides of these recesses 18 are provided with a step-down or shoulder 19, slightly removed from but adjacent to and on each side of the central cable groove 14. Pivot holes or recesses 20 are also provided in the vertical walls of the said recesses 18.

Any number of these recesses 18 may be provided, one above the other, but I prefer to use four of them as illustrated in the drawings.

A pair of clamping or gripping dogs 21 are mounted, one on each side of the cable groove 14, in the recesses 18. Each such dog 21 is provided with a head 22 adapted to engage the cable and to cooperate with the head of the opposite dog to firmly grip or clamp the cable 2 between them (Fig. 8) when the grapple 7 is raised in relation to the cable 2, but to permit said cable 2 to pass freely between them when the grapple 7 is lowered over the said cable 2. Each head 22 is provided with a shoulder or step 23 adapted to engage the shoulder or step 19 when it is down in its gripping position (Fig. 8) whereby the gripping strain is transferred directly from the heads 22 to both of the parts 10 and 11 of the grapple without straining the pivots of the said dogs. The dogs 21 are pivoted in the recesses 18 by suitable pivots mounted in the above described recesses 20 in the vertical walls of the recesses 18. The heads 22 of the dogs are shaped in the usual manner whereby they extend further into the cable groove 14 when they are pulled downward about their pivots than when they are pulled upward thereon (Figs. 8 and 7).

Thus it will be seen that my apparatus provides a means of locating the wreck by the floating rafts 5 attached thereto through the light lines 3, and that these same lines 3 are not connected directly to the wreck but through the short length of heavy cable 2 permanently attached thereto; also, that the said light line 3 forms an effective guiding means whereby the grapple is led to the wreck and is enabled to grip it in the prescribed manner; also that the heavy cable required for lifting the wreck is not carried by the raft, which would require a very large raft, but by the wrecking vessel, and is brought to the wreck only as desired, thereby greatly reducing the cost of the equipment for an owner of several ships, since the same cables would be required for all his vessels of a similar size.

It will be understood that many changes may be made in the details of this invention without departing from the ideas thereof set forth in the appended claim.

Having therefore described my invention, what I claim is:—

A grapple for sunken ships comprising a short heavy hull cable permanently attached to the ship hull and adapted to apply a sub-

stantial raising force thereto; two plates attached together; complementary grooves formed in the contiguous faces of said plates and adapted to receive the heavy hull cable therein; complementary lateral recesses formed in the contiguous faces of said plates and arranged in opposed pairs; complementary pivoted dogs mounted in said recesses, on opposite sides of said cable grooves and

adapted to clamp the cable between them 10 when said plates are raised; a hoisting cable; and independent links connecting the end of said hoisting cable to each said plate, whereby said plates may be separated to admit a cable into said groove without disconnecting 15 them from said hoisting cable.

ELMER C. JACOBSON.
